UNITED STATES PATENT OFFICE.

LEE S. CHADWICK, OF SHAKER HEIGHTS, OHIO, ASSIGNEE TO PERFECTION STOVE COMPANY, OF CLEVELAND, OHIO, A CORPORATION OF OHIO.

OIL BURNER.

Application filed November 23, 1922. Serial No. 602,740.

Reference is made to my former application, Serial No. 528,813, for automatic wick stops, filed January 12, 1922, which has matured into Patent 1,471,542, issued October 23, 1923.

My present invention relates to the same subject, and has to do more particularly with improvements which I have evolved in reducing the invention to a more practical 10 and commercial form.

While burners accurately constructed in accordance with my above mentioned application operate in a thoroughly satisfactory manner, it is found that such extreme accuracy of parts as is required to make the former construction operate properly at all times, is somewhat difficult or at least expensive of attainment and therefore not altogether feasible in the manufacture of 20 the burner on an extensive production basis.

The fundamental object of my present invention, therefore, is to construct a burner possessing all of the characteristics, merits and advantages of my earlier burner and 25 which is better adapted to establish manufacturing methods and conditions, to the ends that its production may be cheapened and expedited and its satisfactory operation and its easy and convenient manipulation 30 assured.

As will be seen by reference to the above mentioned application, and as will appear hereinafter, the wick stop mechanism incorporated in my burner co-acts with the 35 wick adjusting or raising means to limit the latter's movement and thereby stop the wick at a predetermined elevation. The stop mechanism has connection with the air distributing member or flame spreader and 40 it is through a part of said member being engaged by the burned end of the wick and the member and consequently the stop mechanism lifted by the wick, that the stop mechanism is coupled with the wick adjusting means, and after the wick adjusting 45 means and stop mechanism are so coupled together, the former, through the intervention of the latter, lifts the air distributing member or flame spreader from the wick 50 immediately to a position wherein its functions purely as an air distributing member after which the adjusting means may be manipulated to adjust the wick to any position within its burning range, the upward 55 movement of the wick being arrested

through the restraining influence of the stop mechanism upon the adjusting means.

Now, unless the parts are accurately made and fitted together, there is liable to be a certain amount of looseness in the various

60

connections between the wick raising or adjusting means and the wick, and between said means, through the wick stop mechanism, and the air distributing member or flame spreader. Consequently, the very im- 65

portant proper relation between the burned end of the wick and the adjacent part of the air distributing member or flame spreader is apt to be disturbed which would result in obtaining an improper range of flame 70

heights; and under some conditions as where there is an appreciable amount of lost motion between the wick adjusting means and the wick, the descent of the wick might be so delayed as to permit the air distribut- 75

ing member or flame spreader to overtake

and engage the wick on its downward move- 80

ment, even to the extent of binding or lock- 85

ing the mechanism because of the fact that the air distributing member or flame spreader is positively moved downwardly at a considerably higher rate of speed than the wick. Furthermore, the portion of the flame spreader which has become intensely heated during the operation of the burner, 90

by engaging the oil soaked wick, produces a smoke or smudge of disagreeable odor, and is liable to create a very dangerous condition by the generation of gases which may be ignited by a dilatory flame or by the 95

highly heated parts of the burner or by in- 100

candescent carbon particles thereon.

A somewhat more limited object of my present invention, therefore, is to introduce, 105

somewhere in the connections between the

wick raising or adjusting means and the air

controlling member or flame spreader, suffi- 110

cient lost motion to offset the inherent lost

motion between the adjusting means and the

wick, thereby to retard the descent of said

member at least equal to the maximum re- 115

tardation of the wick, so that regardless of

the play in the connections between the

wick raising or adjusting means and the

wick, the wick may be adjusted to any posi- 120

tion within and below its burning range—

from its high position to a position wherein

the fire is extremely low, lower than was

possible of accomplishment in my former

construction, and further to a position so far

110

down within the wick tubes that the flame is extinguished and which is below the maximum low position of the part of the air distributing member or flame spreader where-
5 with the wick engages—before the air distributing member or flame spreader starts to descend, thus obviating any possible occurrence of the undesirable condition above set forth.

10 I preferably incorporate a "lost motion" connection between the wick raising spindle and the ratchet wheel which is mounted upon said spindle and through which the wick stop mechanism is coupled with the spindle; 15 and it follows as a further object to provide a simple, but very reliable "lost motion" connection between said parts which is economical of production and convenient of assembly; and in order to insure against the 20 ratchet wheel being rotated with the spindle, through its frictional engagement therewith, before the play in the "lost motion" connection is taken up, I provide a brake for said wheel which imposes a drag thereon superior to the frictional engagement 25 of the wheel with the spindle.

Among the other objects of the invention, which pertain more particularly to structural refinements, are the provisions of an 30 anti-friction device for supporting the movable element through which the air distributing member or flame spreader is sustained at a definite elevation, thereby rendering easier the operation of the burner than is the case 35 with my former construction where the said element is required to ride over a stationary bearing surface; and to equip the locking pin of the air distributing member or flame spreader with a sleeve of brass or like metal 40 where it cooperates with steel guiding parts so as to prevent such a rusting of the parts as would interfere with their free relative movement.

45 The foregoing object, and others which will appear as this description proceeds, are attained in the construction illustrated in the accompanying drawings wherein Fig. 1 represents a central vertical section through a burner embodying my invention; Fig. 2 is a fragmentary sectional plan view on the line 2—2 of Fig. 1; Fig. 3 is a sectional side elevation of the burner as though viewed from the left of Fig. 1; Fig. 4 is a view, similar to Fig. 3, showing the wick elevated 50 and the wick stop mechanism in a corresponding position; Fig. 5 is an elevational detail of the lower portion of the burner, as though looking from the right of Fig. 4; Fig. 6 is a sectional detail on the correspondingly numbered line of Fig. 4; Figs. 7 and 55 8 are fragmentary vertical sections through the burner, Fig. 7 showing the wick fully elevated and the wick stop mechanism in the position occupied when the wick is fully elevated, and Fig. 8 showing the wick 60

lowered while the wick stop mechanism remains in the position illustrated in the preceding view, the views thus serving to indicate the extent of the relative movement permitted between the wick raising means or 70 spindle and the wick stop mechanism by virtue of the "lost motion" connection between the two; Fig. 9 is a sectional detail of the "lost motion" connection, the plane of section being indicated by the line 9—9 75 of Fig. 7; Fig. 10 is a sectional detail on the line 10—10 of Fig. 8; Fig. 11 is a fragmentary perspective view of a bracket by means of which certain parts of the stop mechanism are supported and guided, and it includes the 80 anti-friction bearing that supports the stop plate or movable element through which the air distributing member or flame spreader is sustained at a given elevation; and Fig. 12 is a perspective view of the stop plate. 85

The burner comprises inner and outer wick tubes 1 and 2, respectively, that are joined together at their lower ends by an annular wall 3, thereby to enclose a wick space 4 to which liquid fuel may be supplied through a fitting 5. The inner wick tube, as is best illustrated in Fig. 2, has a reentrant portion 6 to provide an offset 7 of the wick space. The offset 7 is closed at its lower end by a wall 8, which may be an extension of the former wall 3, and at its upper end by a wall 9 from which rises a sleeve 10 through which a rod 11 is guided, the lower portion of the rod occupying the inner part of the offset 7. Secured to the lower end of the rod is a wick support 12 which, in the present instance, is shown as of the same design and construction as that disclosed in the co-pending application of myself and Marc Resek, Serial No. 596,970 filed October 26, 1922. The elevator is of segmental shape, as shown in Fig. 2, and extends substantially half-way around the wick space and at its middle has an arm through which the before mentioned connection is made with the rod 11. A cylindrical wick 15, equipped with the usual carrier 16, occupies the wick space and rests upon slightly elevated seats or bearing portions 17 at the ends of the wick support (see Fig. 3). The wick is adapted 100 to be separably connected to the support through grips 18 which extends upwardly from the ends of the elevator and have in-turned lips or flanges 19 at their upper ends which engage over the corresponding edge 105 of the wick carrier 16. This construction is fully disclosed in the above mentioned application, Serial No. 596,970. 110

115 As will also more clearly appear from the application just referred to, the upper end of the rod 11 has connection with a rack member 20 which is of channel formation and embraces the reentrant portion 6 of the inner wick tube, as shown in Figs. 1 and 2. One 120 of the side flanges of the member 20 is pro- 125

vided with a series of transverse slots 21 that are equally spaced apart and extend upwardly a suitable distance from the lower end of the member thereby to effect a rack 5 wherewith a pinion 22 meshes (Fig. 9) that is secured to a spindle 23, journaled within opposed branches 25 and 26 of a bracket 27 that is secured to and depends from the burner, the horizontal portion of the bracket 10 having an opening through which the rack member 20 operates. The outer end of the spindle 23 is equipped with a suitable operating handle or hand wheel 28 by means of which the spindle may be rotated. 15 It is clear from the above that when the spindle is rotated it will cause the rack to be moved vertically to similarly adjust the wick by reason of its connection therewith through the rod 11, wick elevator 12 and 20 grips 18. Supported for vertical movement within the upper end of the inner wick tube is an annulus or spanner 30 from which a frame 31 depends, the frame being guided at its 25 lower end by the rear branch 26 of the bracket 27 shown in perspective in Figure 11. In order to properly guide the frame, the lower end of said branch is provided with an overturned lug 33 which embraces 30 one edge of the frame, and with a laterally and then rearwardly turned portion 34 which is engaged about the opposite edge of the frame. The portion 34 is spaced further from the body portion of the branch 26 35 than is the lug 33 for a purpose which shall presently appear, and the portion 34 has joined to it, through an integral neck 35, a head 36. Journaled upon a suitable bearing member 37 that is carried by the head 36 is an anti-friction roller 38. In the present instance the bearing member 37 is shown as a shouldered rivet, and the roller 40 is preferably recessed to receive the head 39 thereof (see Figure 6.) Being so formed, 45 the roller has a comparatively wide peripheral bearing face, is reduced in width where it bears upon the body of the rivet so as to lessen the tendency to bind by an uneven distribution of pressure thereon 50 axially of the rivet, and the space between the rivet head and the adjacent surface of the roller is protected by the overhang of the roller against an accumulation of dust or char and gummy oil deposits which 55 might be likely to settle thereon as they drop through the burner.

Pivottally connected at 40 to the frame 31 is a stop plate 41 incorporating a bendable and therefore adjustable stop 42 which is arranged to engage one edge of the frame 31 to limit the angular movement of the stop plate with respect to the frame in one direction. This stop plate corresponds to what I termed the pawl carrying member in my application Serial No. 528,813, first

above referred to. It was so termed by reason of the fact that it carries a pawl. The pawl in the present instance is designated 43 and it is preferably formed integral with the plate, and has an inwardly directed upper end for engagement with the teeth of the ratchet wheel 45 that is carried by the spindle 23. In my earlier construction, shown in the application just referred to, the ratchet wheel was secured rigidly to the 70 wick adjusting spindle. In my present construction, the wheel 45 is dished and has a sleeved hub 46 which is rotatably supported upon the neck 47 of a circular head 48 that is fixed to the end of the spindle 23, the head 48 lying within the dished portion of the wheel. As will be seen more clearly from Figure 9, the spindle 23 is reduced in diameter for a suitable distance from its inner end and the reduced portion is flattened along one side. The pinion 22 is first applied to the reduced end of the spindle and engages the shoulder produced by the adjacent enlargement, the aperture of the pinion being of a shape corresponding to 80 the cross-sectional shape of the flattened reduced portion of the spindle so that it is held against rotation with respect thereto. A spacer 50 is interposed between the pinion 22 and the neck 47 of the head 48 and 85 the same is somewhat greater in diameter than the neck so as to confine between it and the head 48 the hub 46 of the ratchet wheel. The head 48 has a peripheral notch 51 into which projects a lug 52 of the wheel, the lug being of considerably less lateral extent than the notch. This, therefore, provides the "lost motion" connection between the spindle and the ratchet wheel 90 hereinbefore referred to, and through it, 100 the wheel and spindle have considerable independent movement.

To insure the spindle's having movement independently of that of the ratchet wheel under certain conditions, and to avoid the 110 friction between the hub of the ratchet wheel and the neck of the head 48 from interfering with such independent movement, I provide a brake for the ratchet wheel in the nature of a resilient U-shaped member 115 55, which is secured to the inner wick tube adjacent the ratchet wheel and embraces the edge of the latter so as to impose a drag thereon. The purpose of the brake will be better understood from the description of 120 the operation of the burner which is to follow.

While the head 48 may be secured in any suitable manner to the spindle, my present 125 preferred method of accomplishing this is by depositing solder within the joint between the head and the spindle; and in order to accommodate sufficient solder to make this connection thoroughly effective, 130 I make the aperture in the neck of the head

cylindrical for a suitable distance inwardly from its rear end and throughout the remainder of its length of a shape corresponding to that of the reduced flattened portion of the spindle. This leaves a pocket for a liberal supply of solder which is indicated at 58.

While it is advantageous to have the pawl 43 capable of a limited swinging movement, 10 it must be restrained against undue angular movement and this I accomplish by providing a member 60 that is secured at 61 to the stop plate and has a notch 63 which is little wider than the pawl is thick and which 15 embraces the pawl.

Reposing within the upper end of the burner is the air distributing member or flame spreader 65 which rests, through its body portion 66, upon the spanner 30. The 20 member is adapted to be latched to the spanner by the engagement of the keeper portions 67 of tumblers 68 with an annular shoulder 69 of said member. The tumblers are pivoted at 70 to the frame 31 and they 25 are confined to a limited angular movement by lugs 71 of the frame which project through holes 72 in the tumblers.

The tumblers are adapted to be forced apart with their keeper portions in holding 30 engagement with the shoulder 69 by a pin 75 that is slidably carried by the air distributing member or flame spreader and constitutes a lifting means therefor by extending upwardly through the top of said member 35 where it is provided with a convenient grip 76. The neck 77 of the pin 75 is guided through aligning apertures formed in the top wall of the member, and in a fitting 78 that depends from said 40 wall. The flame spreader parts are preferably constructed of steel, suitably treated so as to make it as nearly rust proof as practicable, but by reason of the sliding of the neck of the pin through the guiding 45 parts they are apt to become worn and therefore liable to rust. To prevent an accumulation of rust such as would interfere with the operation of the parts, I prefer to encase the neck of the pin in a relatively thin sleeve 50 79 of brass or other material immune from rust. Thus, by the use of a comparatively thin sleeve, I economically attain as good results as if the entire pin were made of brass or the like. The air distributing member 55 or flame spreader is provided with the usual flange 80 and top 81 which project out over the annular wick space; the flange being directed downwardly at its edge so as to project into the wick space when the 60 flame spreader is in its lowest position. Several forms of latch mechanisms, including the one herein illustrated (excepting the sleeve 79), for locking the air distributing member or flame spreader to the spanner, 65 are disclosed in an application of myself

and Marc Resek, Serial No. 528,833, filed January 12, 1922.

In describing the operation of the burner we shall assume that, in starting, the parts are in the position shown in Figs. 1 and 3. 70 To elevate the wick to burning position the spindle 23 is turned in the direction indicated by the arrows in Fig. 1. This will result, through the following connections: pinion 22, rack member 20, rod 11 and wick support 12, in elevating the wick, the wick engaging the flange 80 of the flame spreader, lifts the flame spreader and with it the frame 31 and stop plate 41. The stop plate, being guided as hereinbefore explained, is confined for a period to a vertical course of movement which brings the nose of the pawl 43 into the range of the teeth of the ratchet wheel 45. The wheel then, through one of its teeth, picks up the pawl and, through the 80 pawl, lifts the stop plate 41, the frame 31, the spanner 30, and the flame spreader which is supported thereon. The upward movement of the parts continues until the arcuate lower edge of the stop plate rides over and is supported by the roller 38. This roller, therefore, determines the elevation of the flame spreader and positions the flange 80 in proper relation to the upper ends of the wick tubes. It may be explained at this 85 point that this position of the flame spreader may be adjusted to a nicety by raising or lowering the roller 38 through the bending of the neck 35 which connects the roller supporting head 36 to the part 34 of the bracket 100 branch 26.

The angular movement of the stop plate 41, after its lower edge escapes over the roller 38, determines the extent to which the spindle 23 may be rotated to further elevate the wick after the flame spreader has come to rest. This is because the spindle is locked to the stop plate through the pawl 43 and the stop plate is brought to rest by the engagement of the stop 42 thereof with 105 the adjacent edge of the frame 31. When the parts are in this condition, as indicated in Figs. 4 and 7, the wick is in high position. Now, by reason of the "lost motion" connection hereinbefore described between 110 the spindle and the ratchet wheel, the wick may be lowered to any point within its burning range without affecting the position of the ratchet wheel which, it will be remembered, is retained against accidental 115 movement, by the brake 55. It is not until the wick is well down that the spindle picks up the ratchet wheel and starts to rotate it in a direction which, when the lower arcuate edge of the stop plate 41 rides off the 120 roller 38, will result in the lowering of the flame spreader.

Having thus described my invention, what I claim is:

1. In an oil burner of the character set 130

forth, the combination with the wick, of adjusting means for raising and lowering the wick, stop mechanism adapted to be coupled with the wick adjusting means and having a limited scope of movement thereby to restrain said means against raising the wick above a predetermined position, a member connected to the stop mechanism and arranged in the path 10 of the wick so that the wick engages and lifts said member and, through it, couples the stop mechanism with the wick adjusting means, said mechanism thereafter serving to lift, through the action of the adjusting means, the member from the wick and sustain the same at a given elevation, and a "lost motion" connection between the means and mechanism whereby the means is permitted to operate for an interval independently of the mechanism thereby to lower the wick an appreciable distance before the mechanism is actuated in a direction to lower the aforesaid member.

2. In an oil burner of the character set forth the combination with the wick, of adjusting means for raising and lowering the wick, stop mechanism adapted to be coupled with the wick adjusting means and having a limited scope of movement thereby to restrain said means against raising the wick above a predetermined position, a member connected to the stop mechanism and arranged in the path of the wick so that the wick engages and lifts said member and, through it, couples the stop mechanism with the wick adjusting means, said mechanism thereafter serving to lift, through the action of the adjusting means, the member from the wick and sustain the same at a given elevation, a "lost motion" connection between the means and mechanism whereby the means is permitted to operate for an interval independently of the mechanism thereby to lower the wick an appreciable distance before the mechanism is actuated in a direction to lower the aforesaid member, and means restraining the stop mechanism against movement during said interval of time.

3. In an oil burner of the character set forth, the combination with the wick, of adjusting means for raising and lowering the wick, a member arranged in the path of the wick and adapted to be engaged and lifted by the wick when the latter is elevated, mechanism coupled with the wick adjusting means through the lifting of said member and serving to lift the member, through the action of the adjusting means, from the wick and sustain the same at a given elevation, a stop rendered effective by said mechanism to restrain the adjusting means against raising the wick above a predetermined position, and a "lost motion" connection between the adjusting means and the aforesaid mem-

ber which permits said means to operate independently of the mechanism which connects said means with said member.

4. In an oil burner of the character set forth, in combination with the wick, stop mechanism limiting the upward movement of the wick, means for rendering the stop mechanism operative, said means incorporating a member that is adapted to be engaged and moved by the burned portion of the wick and arranged to automatically withdraw therefrom when the wick is in burning position, and means preventing the descent of said member while the wick occupies a position within its burning range.

5. In a burner of the character set forth, the combination of wick adjusting means, a member arranged to be engaged and lifted by the wick, and connections between said member and the wick adjusting means involving a stop for said means and a lifting means for the member, said connections including a lost motion device insuring depression of the wick beyond reach of the member when the wick and member are lowered by the wick adjusting means.

6. In a burner of the character set forth, the combination with the wick, of adjusting means for raising and lowering the wick, a ratchet wheel having a "lost motion" connection with and adapted to be rotated by the wick adjusting means, a member arranged to be engaged and moved by the wick, a pawl carrying element connected to said member, a pawl on said element adapted to be engaged with a tooth of the ratchet wheel when said element is elevated by the aforesaid member, the connections thus established between the ratchet wheel and said member causing said member to be withdrawn from the wick through the action of the wick adjusting means, and means limiting the rotation of the ratchet wheel thereby to arrest movement of the wick adjusting means.

7. In a burner of the character set forth, the combination with the wick, of adjusting means for raising and lowering the wick, a ratchet wheel having a "lost motion" connection with and adapted to be rotated by the wick adjusting means, a member arranged to be engaged and moved by the wick, a pawl carrying element connected to said member, a pawl on said element adapted to be engaged with a tooth of the ratchet wheel when said element is elevated by the aforesaid member, the connections thus established between the ratchet wheel and said member causing said member to be withdrawn from the wick through the action of the wick adjusting means, means limiting the rotation of the ratchet wheel thereby to arrest movement of the wick adjusting means, and means for retarding the rotation of the ratchet wheel.

8. In a burner of the character set forth, the combination with the wick, of rotative wick adjusting means, a ratchet wheel having a "lost motion" connection with said means, a member arranged to be engaged and moved by the wick, a frame movable with said member, a pawl carrying element pivotally connected to the frame so as to be capable of both a vertical movement with the frame and a rotative movement with the ratchet wheel, means restricting the initial movement of said element to a vertical course which is effective until said element has been raised to a position wherein its pivotal connection with the frame is substantially coincident with the rotating axis of the ratchet wheel, a pawl carried by said element which is engaged with a tooth of the ratchet wheel during the initial vertical movement of said element, the element rotating with the ratchet wheel after its pivotal axis has assumed substantial alignment with the rotating axis of the ratchet wheel, and a stop for limiting the rotative movement of the element.

9. In an oil burner, in combination with the wick, means for raising and lowering the wick, a flame spreader, and means acting automatically to elevate the flame spreader when the wick is at a given point in its upward travel and to lower the flame spreader when the wick is at a different point in its downward travel.

10. In an oil burner, in combination with the wick, means for raising and lowering the wick, a flame spreader, and means operated by the wick raising and lowering means for elevating the flame spreader when the wick is at a given point in its upward travel and for lowering the flame spreader when the wick is at a different point in its downward travel.

11. In an oil burner, in combination with the wick, means for raising and lowering the wick, a flame spreader, mechanism through the intervention of which the wick raising and lowering means elevates the flame spreader when the wick is at a given point in its upward travel and lowers the flame spreader when the wick is at a different point in its downward travel, and a stop actuated by said mechanism for restraining the wick raising and lowering means against raising the wick above a predetermined point.

12. In a burner of the character set forth, in combination, a supporting structure, wick adjusting means, an air controlling member, means supporting the air controlling member, an element connected to the supporting means for limited movement with respect thereto and being adapted to assume driving connection with the wick adjusting means thereby to limit the movement of the latter, an anti-friction bearing over and in

contact with which said element is arranged to ride when connected with and moved by the wick adjusting means, the element serving the while to sustain the aforesaid supporting means in a position to properly space the air controlling member from the wick.

13. In a burner of the character set forth, in combination with the wick, a rotatable spindle, wick adjusting means operated thereby for raising and lowering the wick, an air controlling member, a movable support therefor, an element pivoted to the support, said element being capable of limited angular movement and adapted to be connected to the spindle to be oscillated thereby and to limit the spindle's rotation, and an anti-friction bearing whereon said element rides during its movement by the spindle thereby to sustain the support at an elevation to properly space the air controlling member from the wick.

14. In a burner of the character set forth, in combination with the body structure of the burner, a rotatable spindle journaled therein, wick adjusting means operated by the spindle for raising and lowering the wick, an air controlling member, a support therefor that is movably sustained by the body structure, an element pivoted to the support, said element being capable of limited angular movement and adapted to be connected to the spindle to be oscillated thereby and to limit the spindle's rotation, a head adjustably supported by the body structure, and an anti-friction bearing rotatably supported by the head and whereon the element rides during its movement so as to sustain the support at an elevation to properly space the air controlling member from the wick, the spacing of said member from the wick being made variable through the adjustment of the aforesaid head.

15. In a burner of the character set forth, in combination with the body structure of the burner, wick adjusting means, an air controlling member and its support movably sustained by the body structure, an element movable on the support and through which the wick adjusting means is adapted to have connection with said support to lift the support and move the element with respect thereto, and an anti-friction bearing carried by the structure for guiding the body support and sustaining the element during the latter's movement.

16. In a burner of the character set forth, in combination, a supporting structure, wick adjusting means, an air controlling member, means supporting the air controlling member, an element connected to the supporting means for limited movement with respect thereto and being adapted to assume driving connection with the wick adjusting means thereby to limit the movement of the latter,

- a bearing member carried by the structure, and a roller journaled on said bearing member, the bearing member having a head, the roller being recessed to receive the head, the 5 aforesaid element being arranged to ride upon said roller during its movement thereby to sustain the supporting means in position to properly space the air controlling member from the wick.
- 10 17. In a burner of the character set forth, in combination with the wick, adjusting means for raising and lowering the wick including a rotatable spindle, a head secured to the spindle, a ratchet wheel rotatable on the axis of the spindle, said wheel and said head having one a tongue and the other a recess for the reception of the tongue and which is of greater circumferential extent than the tongue whereby a "lost motion" 15 driving connection is effected between the wheel and the head, a member arranged to be engaged and moved by the wick, a pawl carrying element connected to said member, a pawl on said element adapted to be engaged with a tooth of the ratchet wheel when said element is elevated by the aforesaid member, the 20 connections thus established between the ratchet wheel and said member causing said member to be withdrawn from the wick through the action of the wick adjusting means, and means limiting the rotation of the ratchet wheel thereby to arrest movement of the wick adjusting means.
- 25 18. In a burner of the character set forth, in combination with the wick, adjusting means for raising and lowering the wick including a rotatable spindle, a head having a neck secured to the spindle, a ratchet wheel 30 gaged with a tooth of the ratchet wheel when said element is elevated by the aforesaid member, the connections thus established between the ratchet wheel and said member causing said member to be withdrawn from the wick through the action of the wick adjusting means, and means limiting the rotation of the ratchet wheel thereby to arrest movement of the wick adjusting means.
- 35 19. In a burner of the character set forth, in combination with the wick, adjusting means for raising and lowering the wick including a rotatable spindle, a head secured to the spindle, a ratchet wheel rotatable on the axis of the spindle, said wheel and said head having one a tongue and the other a recess for the reception of the tongue and which is of greater circumferential extent than the tongue whereby a "lost motion" 40 driving connection is effected between the spindle and the ratchet wheel, a member arranged to be engaged and moved by the wick, a pawl carrying element connected to said member, a pawl on said element adapted to be engaged with a tooth of the ratchet wheel when said element is elevated by the aforesaid member, the connections thus established between the ratchet wheel and said member causing said member to be withdrawn from the wick through the action of the wick adjusting means, means limiting the rotation of the ratchet wheel thereby to arrest movement of the wick adjusting means, and a brake member frictionally engaging the ratchet wheel to retard the latter's movement.
